TAPE-DISPENSING MECHANISMS

William S. Shee, Woodbridge, Conn., assignor to Derby Sealers, Incorporated, Derby, Conn., a corporation of Connecticut

Application December 29, 1951, Serial No. 264,199

2 Claims. (Cl. 271—2.4)

This invention relates to a device for dispensing tape and more especially pressure-sensitive tape or tape that is tacky upon one side.

Machines for dispensing tape of this kind provide in some instances rollers or other feed devices for drawing the tape from the roll and delivering it or dispensing it in the form of a free length projecting from the machine, which free length may be grasped by the user. In some instances the user draws the free end across the blade of a severing member so that it may be severed from the remainder of the tape on the supply roll. The present invention relates to a device which is provided with tape-feeding means or means for drawing the tape from the supply roll rather than a device in which the tape is grasped by the fingers and drawn from the supply roll by a pull exerted directly by the user.

When a length of tape has been dispensed by the machine and the free end of the dispensed tape depends downwardly, it is likely to come into contact with a part of the machine or even with the supporting surface upon which the machine rests, and as the tacky side of the tape will, of course, cling to any object with which it comes in contact, this presents considerable inconvenience. It is contemplated by the present invention to provide a support which may be engaged by the free end of the dispensed tape so that the tape will be prevented from coming in contact with other objects. At the same time the support will be of such a character that it will not prevent the user grasping the free end of the tape to apply it or to tear it off against the severing blade, if the latter operation is necessary.

Also, the member which supports the free end of the tape is adjustable and, as illustrated, is pivotally mounted so that it may be swung about this pivot to various positions in front of the feeding mechanism or to a position below this mechanism where it is out of the way and inoperative. The supporting member is also adjustable toward and from the feed mechanism as well as being adjustable about its pivot, and to this end is mounted in slots in a pair of pivoted arms, one at each end of the supporting member so that it may be adjusted along these arms in the slots.

One object of the invention is to provide a tape-dispensing mechanism with means to engage and support the free end of the tape which has been drawn from the supply roll.

Another object of the invention is to provide a tape-dispensing mechanism having feeding means for drawing a length of tape from a supply roll with a supporting element to support the length of tape which has been dispensed, the supporting element being mounted forwardly of the feeding mechanism.

A still further object of the invention is to provide, in a tape-dispensing mechanism of the character described, a tape-end-supporting member mounted forwardly of the feed mechanism, which member is adjustable toward and from the feed mechanism in the direction of the path of the tape.

2

Still another object of the invention is to provide a supporting member for the free end of the tape in a tape-dispensing mechanism, which supporting member will be adjustable transversely of the path of the tape.

To these and other ends the invention consists in the novel features and combinations of parts to be herein-after described and claimed.

In the accompanying drawings:

Fig. 1 is a front elevational view of a tape-dispensing mechanism embodying my invention;

Fig. 2 is a partial sectional view on line 2—2 of Fig. 1; and

Fig. 3 is a view similar to Fig. 2 showing the parts in another position.

To illustrate a preferred embodiment of my invention, I have shown in the drawings a tape-dispensing mechanism comprising a frame or case having upstanding side members 10 and 11 and a removable cover 12. Rotatably mounted in the side members 10 and 11 are shafts 13 and 14, the shaft 13 supporting a feed roller and the shaft 14 supporting a stripping roller.

It will be understood that the invention is not limited to a particular type of feed roller or a particular type of stripping roller but, as shown, the shaft 13 is of polygonal form between its bearings, and upon this shaft are mounted a plurality of spaced disks 15 having serrated edges 16 with which the tape engages to be drawn from the supply roll (not shown).

Also, the shaft 14 of the stripping roll is shown as of rectangular cross section, and upon this shaft are non-rotatably mounted a plurality of spaced stripping disks 17 having serrated edges 18 which engage the tape, shown at 19, and strip it from the feeding disks 15. As shown in Fig. 2, the stripping disks 17 overlap or extend between the spaced disks 15 of the feed roll so that the tape will not be permitted to be carried around the latter.

Any suitable means may be employed for driving the shafts 13 and 14, such means being well known in the art and, as is also the general practice, the stripping roll will be driven at a peripheral speed greater than that of the feed roll so that the disks of the stripping roll will thus be stripped from the dispensed tape. As illustrated, the device is provided with a lever or oscillating handle 20 pivoted at 21, which handle is adapted to drive the feed and stripping rolls. A severing member 23 is secured to a supporting plate 24, the latter being carried by lugs 25 formed integrally with the frame members 10 and 11. The blade 23 may lie between the support 24 and a backing member 26 secured to the support so that it may be made of relatively thin material and at the same time be held rigidly in place. The severing edge of this member projects toward the bite between the feed and stripping rolls so that the tape will be severed at a point adjacent the surface of the feed roll.

A rod 30 is mounted in the frame members 10 and 11, the ends of this rod projecting beyond the frame members and providing pivot means for a pair of links 31 which are provided with elongated slots 32. The end portions of the rod 30 are received in the slots 32 and the arms or links 31 may be held in place by nuts 33 received on the threaded ends of the rod 30. It will be understood that the members 31 may be pivotally swung to any desired position about the rod 30, as shown in Fig. 3, and may be fixed in any adjusted position by tightening the nuts 33.

A supporting member for the free end of the tape is carried by the arms 31. This supporting member is in the form of a relatively small elongated rod 35 which extends transversely across the frame, the ends of this rod being slidably mounted in the slots 32 of the arms 31. Nuts 36 may be threaded upon the ends of the rod 35, and the nuts may be tightened against the arms

70

in order to hold the rod 35 in any desired position in the slot 32. Thus the rod 35 which is the supporting member for the free end of the tape may be employed at the extreme outer ends of the slots 32, as shown in Fig. 2, or at a point intermediate the ends of the slots, as shown, for example, in Fig. 3. That is, the rod 35 will be adjusted toward and from the member 30 in the slot 32, and may be secured in any desired position by tightening the nuts 36.

Also, of course, the rod 35 may be swung pivotally about the member 30 so that it may stand outwardly from the stripping roll 17, as shown in full lines in Figs. 2 and 3, or may stand in an out-of-the-way position below the stripping roll 17, as shown in dotted lines in Fig. 3, or may be swung to any other desired angular position.

In operation the lever or handle 21 is drawn downwardly from the position shown in Fig. 1, and the feed and stripping rolls will be rotated to draw a length of tape from a supply roll supported by the frame or case of the machine and dispense this tape forwardly of the stripping roll 17, as shown at 19. The dispensed end of the tape moves outwardly over the member 30 which, as shown in Figs. 2 and 3, is disposed in a position relatively close to the surface of the stripping roll.

If a relatively long length of tape is being dispensed, the supporting member 35 may be disposed at the extreme ends of the slots 32, as shown in Fig. 2, and the tape will be supported adjacent its free end by the rod 35, as shown in this figure. The user may insert his forefinger below the tape between the members 30 and 35, as shown at 37 in Fig. 2, and then grasping the tape between the thumb and forefinger move it upwardly against the severing blade 23 to sever it from that portion of the tape adjacent the supply roll.

If a relatively short length of tape is being dispensed, the supporting member 35 may be moved toward the pivot member 30 so that it will contact the edge of the tape, as shown in Fig. 3, and prevent this end of the tape from falling downwardly against the stripping roll or other object.

As the stripper rolls or disks 17 rotate at a greater speed than the feed roll, they act as kickers to kick the tape outwardly whereby it will travel over the lower of the two rods. The natural speed of the tape together with its relative stiffness and the direction given it by the stripper disks will normally maintain it in a position outwardly over the lower rod, as shown in Fig. 2, and it is only when a relatively long length is dispensed that the weight of the dispensed end will be sufficient to cause it to sag against the stripper rolls or the lower part of the machine. At the end of the feeding operation the tape might then be inclined to drop down against the stripper rolls were it not for the rod 35, but during the operation of the machine the speed of the tape together with its stiffness will cause it to travel over the lower rod 35 even though the latter is at its lowermost position. Even a short length of tape will normally span the two rods 30 and 35 when the latter has been adjusted to its upper position so that the rod 35 will, when in operative

position, prevent the tape from falling downwardly in contact with the part of the machine or in contact with the stripper roll.

If the character of the tape being dispensed is such that a support is not necessary, the arms 31 may be swung downwardly to the dotted-line position shown in Fig. 3 where they are in out-of-the-way position so that the tape-end-supporting member 35 may be used or not as desired. In the event that short lengths of tape are dispensed, and also in connection with some kinds of tape, the member 30 will be sufficient to support the free end of the tape so as to prevent it from contacting parts of the machine. In such case the arms 31 may be moved to the dotted-line position shown in Fig. 3 or may, if desired, be entirely removed from the dispenser.

While I have shown and described a preferred embodiment of my invention, it will be understood that it is not to be limited to all of the details shown, but is capable of modification and variation within the spirit of the invention and within the scope of the claims.

What I claim is:

1. A machine for dispensing pressure-sensitive tape comprising a frame, a feed roll rotatably supported thereon to draw the tape from the supply roll, stripper means 25 to strip the tape from the feed roll, a pair of arms pivoted to the frame in spaced relation, one at each side of the frame, adjacent the stripper means and extending forwardly therefrom, a tape-end-supporting rod carried by said arms and extending transversely of the frame to engage the tacky side of the tape and support it from below, said member being adjustable longitudinally of said arms toward and from the frame to various positions along the path of the tape, and said arms being swingable to move said rod to an inoperative position.
2. A machine for dispensing pressure-sensitive tape comprising a frame, a feed roll rotatably mounted on the frame to which the tape adheres, stripper means carried by the frame to strip the tape from the feed roll, a pivot rod carried by the frame and extending transversely 40 thereof adjacent to and forwardly of the stripper means and below the path of the tape, a pair of slotted arms pivoted on said rod in spaced relation, one at each side of the frame and adapted to extend forwardly therefrom, and a tape-end-supporting rod member mounted in said slots in spaced relation to the pivot member, and means for adjusting said member to various positions along the path of the tape while maintaining it parallel to its initial position.
